UNITED STATES PATENT OFFICE

BOWDEN WASHINGTON, OF NEW YORK, AND WILSON AULL, JR., OF ASTORIA, NEW YORK, ASSIGNEES TO REMOTROLE CORPORATION, A CORPORATION OF NEW YORK

RADIORECEPTION

Application filed April 2, 1927. Serial No. 180,381.

The modern broadcast receiver as its quality is improved is becoming heavier and larger and less portable particularly if the batteries are not self-contained and an outdoor antenna and ground are used. It is extremely simple to run an extension cord for the loud speaker from the room containing the radio receiver to any other room in the house or the house may be easily supplied with built-in wiring for this purpose. It is not so simple, however, to employ built-in or flexible wiring to control the tuning and volume of such receiver from a distance.

One object of our invention is to produce a radio receiving system which will enable substantially any broadcast receiver to respond to any desired signal which may be collected by the antenna, and which is within the frequency band of the system, and to have its volume, as well as the frequency received, regulated from a small control unit located a short distance away with no physical connections such as cables, wires, etc. between the two.

Another object of our invention is to produce a system which may be used in conjunction with substantially any modern radio receiver no matter what its frequency range may be, and cause said receiver to be remote controlled both as to volume and wave length over its own or any other desired frequency band without mechanical movement of any parts within the receiver.

Another object of our invention is to produce a system which will convert any receiver having a single fixed resonant frequency into a receiver which will operate over any desired band of frequencies.

Another object is to produce an efficient multi-tube receiver having a single movable electrical tuning member, rather than a multiplicity of tuning members mechanically connected as is current practice.

We utilize a control unit capable of receiving and selecting signals and retransmitting or coupling them to a reproducing receiver. Ordinarily we will provide a band amplifier converter having a receiving antenna system and associated with the output a radiating or

coupling system, for producing a field which influences the control unit.

In our invention the control unit which may be made small, light and readily portable, need have no exterior connections and may be completely self-contained. In other words, its power source and its control elements may be all within the portable control member, or its power supply may be obtained from the alternating current house lines by means of the usual flexible cord and plug. This box may be taken into the dining room, sun porch, or any other part of the house or apartment and both the frequency received and the volume of the sound output may be simply and easily controlled from a distance by means of this box.

Fig. 1 of the drawings shows diagrammatically one embodiment of our invention in conjunction with a broadcast receiver.

Fig. 2 is a schematic wiring diagram of one form of control circuit.

Fig. 3 shows our invention in conjunction with a receiver especially made to coact therewith.

Fig. 4 is a schematic wiring diagram of one simple form of converter embodying a band-pass amplifier which can be used as a part of our system.

The antenna 5 and ground 6 may be of any suitable type. 7 is a band-pass converter-amplifier of any suitable construction covering the desired range of frequencies, as for instance 550 to 1500 k. c. An untuned radiator or coupler 8 may be a loop or coupling coil of moderate size connected in the plate circuit of the last tube of the band-pass amplifier 7. The transformers may be so proportioned or variously "peaked" as to amplify frequencies within the desired band.

9 represents the portable control box or unit having pick-up or input means such as the loop or coil 10, a regenerative detector 19 a tuning control 11, a volume control 12 and suitable batteries 20 and 21. This detector modulates a fixed frequency oscillator 23 having radiating or output coupling means such as the loop or coil 13.

The receiver 14 which may be of any suitable type (or may be built to respond to a

fixed frequency) is provided with a wave interception or coupling device such as the loop or coil 15 and its associated condenser 16. The loop 15 and the condenser 16 may be so proportioned as to have the capacity and the inductance of an average broadcast receiver antenna. If used with an adjustable broadcast receiver this is particularly important in uni-control receivers. The out-put of the receiver is connected in the usual manner to any reproducer such as the loud speaker 17.

Under ordinary conditions of use 8 and 13 may be considered respectively as primaries of very loosely coupled transformers whose secondaries are 10 and 15.

In operation, the antenna system consisting of the antenna 5 and the ground 6 and their associated circuits picks up all signals within range. These signals are substantially uniformly amplified by the band-pass amplifier 7 and radiated from or coupled by the untuned radiator or coupler 8. Then by means of the tuning adjustment 11 of the regenerative detector 19 any one of these relayed signals may be chosen. The intensity of the out-put of said detector may be regulated by the control 12 as a regeneration control or this control 12 may change the intensity of radiation of the fixed wave length oscillator, or the intensity may be controlled by both the regeneration of the modulating detector and the plate voltage of the oscillator by placing the feed-back coil of the detector and a non-inductive variable resistor in the plate circuit of the oscillator on the same shaft, as shown at 12, Fig. 2, thus varying both the strength of oscillation and the strength of modulation.

The oscillator contained in the portable control box 9 may be adjusted to any wave length within the range of the receiver 14 and the receiver 14 is adjusted to receive the same frequency as the output of the control box.

It should be understood that the fixed frequency field which is in part common to the loops or other coupling means 13 and 15 may be changed as to frequency and then fixed, so that if two of these receivers are in use close together an adjustment may be made so that A's control unit will not operate B's receiver and vice versa.

It should also be understood that the band-pass amplifier 7 may be made sufficiently powerful so that an apartment house or locality could be equipped with one of these devices and anyone within a predetermined range would need only a control box 9 and a receiver 14' (Fig. 3).

The frequency chosen for the oscillator within the control box and for the resonant frequency of the receiver 14 (or 14') may preferably be either below or above the desired band, or a frequency differing from the frequencies of any station or stations effective or within range of said receiver in con-

junction with the antenna or coupling device 15.

The band-pass amplifier 7 and its radiating or coupling means 8 form an amplifying relay-station for all signals within its range. One of these signals is chosen by the control 11 of control box 9 and re-radiated or coupled at a fixed frequency by the radiating or couplings means 13 which is associated with the tuning control 11 of the pick-up device 10. The intensity of this radiation may be regulated by the knob 12 which may control the regeneration of the detector or the plate voltage of the oscillator or the intensity may be controlled by any other suitable means. The signal is then coupled by the coupling means 13 to the receiving means 15 at a fixed wave length and is then further amplified, detected and re-amplified at audio frequencies by the receiver 14 or 14'.

It should be understood that the field produced by the coupling means 13 may be adjusted to any desired frequency, for instance to excite a long wave Navy type receiver, used at 14. This receiver might have a frequency range of 100 kilocycles to 15 kilocycles. A point near its point of best response may be chosen but this point should not be in resonance with any nearby transmitter and the oscillator associated with the radiator 13 may be adjusted to this frequency. The receiver 14 may be a short wave receiver in which case the radiation from the control box would be adjusted to a frequency suitable for this type. In other words, our system provides a means for converting substantially any moderately sensitive receiver into a "uni-control" and/or "remote-control" receiver operating over the broadcast band of frequencies or any other band desired.

It should also be understood that the control element 9 for certain purposes may be made sufficiently sensitive so that it can pick up outside signals itself in which case we could dispense with the elements 5, 6, 7 and 8.

One advantage of our system over devices equipped with motors to actuate a single control receiver, said motors having stop, start and reversing switches provided with a cord, is the fact that the dial 11 of our control box 9 may be calibrated to read directly in frequency, wave length or other suitable units, which has not so far been achieved, we believe, with the motor type.

In Fig. 3 is shown diagrammatically another embodiment of our invention which is similar to that just described except for the fact that the receiver 14' may be a fixed frequency receiver having no tuning condensers or controls except that of the receiving member 15 which is adjusted once and for all and then locked and no controls except a filament switch 18. This receiver using fixed inter-stage transformers may be manufactured at an extremely low cost. Such a receiver to-

gether with the band amplifier 7 and control 5 9 constitute the elements necessary to produce a remote control and "single control" receiver at a price comparable with that of an ordinary modern high grade receiver.

We do not wish to limit ourselves to regeneration as a method of sensitizing the receiving means of the control box 9, as any other suitable system of equal or greater sensitivity 10 may be substituted without departing from the spirit of our invention.

The band amplifier-converter 7 according to current practice would contain the usual radio frequency amplifier tubes and filters. 15 The control unit 9 would comprise suitable detector and oscillator tubes arranged in any suitable circuit sufficiently sensitive. The reproducer unit 14 may contain any suitable number of radio frequency amplifier stages, 20 a detector and audio stages of amplification arranged according to any suitable receiving circuit. It is presumed that suitable vacuum tubes will be used.

One type of installation would consist of 25 (a) an amplifier-converter located where most convenient for antenna and ground connection or power supply, (b) the reproducer or receiver proper, with its loud speaker located where the reproduction is most desired, 30 (c) the control unit located at the point from which the reproduction is to be controlled at a distance ordinarily of say 5 to 50 feet, a fraction of a wave length. A plurality of control units might be provided at different 35 points. The reproducer unit might, of course, be adjusted to respond to the frequency of any one of several different control oscillators.

Another type of installation might consist 40 of a combination amplifier-converter and reproducer unit together with a portable or remote control unit.

According to our system considered as a whole, it will be seen that the frequency selection 45 can be effected by the simple adjustment of a single control dial or drum 11 which actuates or adjusts a single tuning element, such as a condenser (Fig. 2). The only other adjustable element ordinarily required would 50 be the volume control by means of knob 12.

It thus becomes unnecessary to accurately "match" several adjustable tuning elements as in the usual single control sets which attempted "matching" is not only difficult and 5 expensive but frequently unsatisfactory.

It should be understood, however, that the invention in its broadest aspect is not limited to details except as they are set forth in the claims or required by the prior art.

6 We claim:

1. A household radio receiving system comprising a band amplifier for receiving and simultaneously amplifying signals of widely varying frequencies, an aperiodic collecting 15 means for said band amplifier, an untuned

radiator for said amplifier, a control unit separate and portable independently of the band amplifier and comprising a detector having a collecting circuit tunable over the band of the amplifier, an oscillator modulated by 70 the rectified selected signal frequency and having an output tuned to a predetermined frequency and a receiver separate from the control unit tuned to the frequency of the oscillator. 75

2. A method of household radio reception which comprises receiving and amplifying without change of frequency, all signals of various frequencies within a broadcast band, radiating said amplified signals, collecting, 80 selecting and demodulating the signal of the desired frequency at a point a short distance away from the amplifier, impressing said demodulated signal upon oscillations of a predetermined frequency, collecting the said signal of predetermined frequency at another point and amplifying, demodulating and converting said signal into sound energy. 85

3. A radio receiving system comprising an untuned signal collector associated with the input of a multi-stage band amplifier capable of amplifying a large band of frequencies without change of frequency but with appropriate change of phase so as to prevent overall regeneration or degeneration, a radiating device associated directly with the output of said band amplifier, a control unit independent of the band amplifier and portable and having a selective collector for selecting the desired signal from said radiating device, a 90 demodulator associated with said collector, an oscillator of predetermined frequency different from the frequency of the received signals and modulated by the output of said demodulator, radiating means for said oscillator and a receiver located a short distance from the control unit and having periodic collecting means adjusted to the frequency of said oscillator, amplifying means, demodulating means, and means for the conversion of 100 electrical energy to sound energy. 105

4. A radio receiving system having a band pass amplifying mesh adapted to simultaneously receive and amplify all signals within a predetermined band with substantial uniformity and to retransmit said signals unchanged in frequency or modulation, a mechanically separate manually portable control unit adapted to select any desired retransmitted signal, demodulate it and further 115 transmit its modulations on a predetermined frequency different from the frequency of the received signals, and a receiver separate and distant from the control unit resonant to said predetermined frequency and including audio amplifying and reproducing means, said receiver being in itself substantially unresponsive to signals of normal field strength. 120

5. A household radio receiving system comprising a band pass amplifying filter having 130

- an output device and adapted to simultaneously broadcast a short distance signal of various frequencies, a reproducing receiver substantially insensitive to the normal broadcast signals and a separate, readily portable control unit located a short distance from said filter and said reproducing receiver and having a selective field collector loosely coupled with the output of the filter for selecting any desired signal frequency from said amplifying filter, means for demodulating the selected signal, an oscillator modulated by said demodulator and means for loosely coupling said oscillator with said reproducing receiver. 70
15. A radio receiving system comprising a band pass amplifying filter having means for initially receiving and amplifying various waves and producing an electric field of the same frequencies as the received signals, a 75
- 20 separately portable control unit having a selective field collector for selecting a desired frequency, a demodulator affected by the selected frequencies, an oscillator modulated by the demodulator and producing an electric field of a predetermined frequency differing from the frequencies of the received signals, and a reproducer separate from the control unit and having a field collector responsive to the field produced by the oscillator and including a detector and an associated loud speaker. 80
